UNITED STATES PATENT OFFICE.

ELMER G. GARTIN, OF CLAREMONT, NEW HAMPSHIRE, ASSIGNOR TO SULLIVAN MACHINERY COMPANY, A CORPORATION OF MASSACHUSETTS.

ROCK-DRILLING MECHANISM.

Application filed December 26, 1922. Serial No. 609,130.

My invention relates to rock drilling mechanisms, and more particularly to improved controlling and feeding mechanisms for use therewith.

5 An object of my invention is to provide an improved rock drilling mechanism. Another object of my invention is to provide an improved rock drilling mechanism having improved feeding means and improved 10 controlling means for the motor of said rock drilling mechanism and for the feeding means thereof. Other objects and advantages of my invention will hereinafter more fully appear.

15 In the accompanying drawings I have shown for purposes of illustration one form which my invention may assume in practice.

In these drawings,—

20 Fig. 1 is a view partially in elevation and partially broken away, showing a drilling mechanism embodying my improved construction.

25 Fig. 2 is an enlarged view partially in central section through the controlling mechanism constituting a portion of the illustrative embodiment of my invention, and partially in elevation.

For purposes of illustration I have shown 30 my invention embodied in a drilling mechanism of the so-called "stoper" type, which mechanism is generally designated 1. This mechanism comprises a usual drilling motor 2 having a piston 3 which is adapted to impart a series of blows to a drill steel 4. As shown, a feeding mechanism of well known form, generally designated 5, cooperates with the drilling motor and comprises a feed cylinder 6 in whose bore 7 a piston 8 having a piston rod 9 is reciprocable, the rod 9 being provided with an abutment engaging point 16 and the piston during operation remaining stationary while the cylinder, together with the drilling motor, advances 45 toward the work in a usual manner.

For the purpose of controlling the operation of the motor 2 and the supply of air to the feed cylinder 6, I have devised an improved controlling mechanism best shown in 50 Figure 2. This mechanism includes a valve casing 12, herein formed upon an intermediate head 13 between the motor 2 and feed cylinder 6, although other positions may of course be selected. The valve casing 12 has a conical bore 14 in which a fixed

bushing 15 is arranged. The bushing 15 likewise has a conical bore 16 within which is rotatable a valve member 17 shaped to fit the interior of the bushing and having within it a chamber 18. Fluid from a supply line 19 is admitted through a port 20 in the bushing and a port 21 in the valve to the chamber 18 and from this chamber it is transmitted through port means, including a passage 21^a leading to the drilling motor. 60 A handle 22 is provided to permit the valve 17 to be rotated in such manner as to control the supply of fluid therethrough. Arranged in axial alignment with the valve 17 and herein rigidly screwed into the stationary bushing 15 is a projecting supporting handle 23 which is, in the present form of my invention, made hollow as at 24 to serve as a storage chamber for lubricant and an automatic lubricant distributing valve 25 of 70 a well-known form is provided to transmit the lubricant from the chamber 24 in suitable quantities and at a gradual rate to the chamber 18 from whence it may be conducted to the motor. The handle 23 has a portion 26 arranged at right angles to the main portion thereof and pivoted within this portion 26 is a control lever 27, one end of which projects to the outside of the member 26 into a suitable position for easy operation by a hand grasping the portion 26. The other end of this lever 27 engages a button 28 upon a stem 29 and is adapted when the lever portion 27 is moved toward parallelism with the handle 26 to move the rod 29 longitudinally against the resistance of a spring 30 which is arranged between a plug 31 in the end of the handle 23 and the button 28. At the opposite end of the stem 29 there is arranged a valve 32, herein formed integral with the stem 29, although it may obviously be made detachable therefrom. This valve 32 is of the end seating type and is adapted to cooperate with the seat 33 formed within the valve member 17 and to control a port 34 passing through the valve into communication with the port 35 which leads to the feed cylinder bore 7. It will be understood that the port 35 is of such construction that turning of the handle 22 to start the motor 2 will bring the port 34 into communication with the port 35. The valve 32 is slightly notched at an angle as at 36 to permit a small and variable quantity of fluid to be supplied to the port 34. The 110

valve member 17 is cut away also as at 37 to facilitate this supply.

From the foregoing description the mode of operation of my invention as shown herein for purposes of illustration will be readily apparent. When it is desired to start drilling, the handle 22 may be controlled to supply air to the chamber 18 and thence to the motor cylinder and to the passage 34, provided the valve 32 be open. A graduated feed is obtained and the force of the feed is readily controlled by manipulation of the lever portion 27, the feed being entirely interrupted when air supply is cut off by the forcing to the left in Fig. 2 of the valve member 32 and graduated quantities of air being admitted through the notch 37 and the groove 36, depending upon the position in which the stem 29 is held by the lever portion 27.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a drilling mechanism, the combination with a drilling motor, a pressure fluid actuated feeding device therefor, and a drill supporting handle projecting laterally therefrom, of independently operable coaxial valves, one of which controls both the feeding device and said motor and the other of which controls only the pressure in said feeding device, said valves having independent operating handles, one of which is rotatable in a plane at an angle to the plane of movement of the other handle, said latter handle being carried by said supporting handle.

2. In a rock drilling mechanism, the combination with a hammer drill and a pressure fluid feeding device attached thereto, of independently operable valves, one of which is located within the other and moves longitudinally thereof, and means including a supporting handle member projecting laterally from said drilling mechanism and means associated therewith for operating one of said valves.

3. In a pressure fluid operated drilling mechanism, the combination with a hammer drill, a pressure fluid feeding device attached thereto, and a supporting handle projecting therefrom of a valve member adjustable to control said drill and said feed, a coaxial valve reciprocable in said handle for exerting a supplemental control on said feed, and controlling means for said valves each operable by one hand of a drill runner.

4. In a pressure fluid operated drilling

mechanism, the combination with a hammer drill motor, a pressure fluid feeding device attached thereto, and a supporting handle projecting therefrom, of a valve member adjustable to control said drill and said feed, a coaxial valve reciprocable in said handle exerting a supplemental control on said feed, and controlling means for said valves each operable by one hand of a drill runner and both moving bodily with said motor during feeding thereof.

5. In a drilling mechanism, the combination with a drilling motor pressure fluid operated feeding means therefor, and a supporting handle projecting therefrom, of controlling means for said motor and feeding means comprising coaxially arranged valves having controlling means respectively arranged at opposite sides of a plane perpendicular to the axes of the valves and including the axis of the feeding means, one of said controlling means being carried by said supporting handle.

6. In a drilling mechanism, the combination with a drilling motor and pressure fluid feeding means therefor, and a supporting handle adapted to be grasped by the operator, of independently operable coaxially arranged valves one of which controls the pressure fluid supply to said feeding means and said drilling motor and the other for controlling only the pressure fluid supply to said feeding means and arranged on said supporting handle, said valves having independent operating handles one of which is rotatable in a plane at an angle to the plane of the other.

7. In a drilling mechanism, the combination with a drilling motor and pressure fluid feeding means therefor and a supporting handle adapted to be grasped by the operator, of independently operable coaxially arranged controlling valves and operating handles therefor disposed at opposite sides of said mechanism, one of said handles being carried by said supporting handle.

8. A drilling mechanism comprising a drilling motor and feeding means therefor, a supporting handle projecting from said mechanism, means for controlling said motor and said feeding means including independently operable valves arranged coaxially with their axes alined with the longitudinal axis of said handle and operating means for one of said valves carried by said supporting handle.

9. A drilling mechanism comprising a drilling motor and feeding means therefor, a supporting handle projecting from said mechanism, and means for controlling said motor and said feeding means including a rotatable valve and a reciprocable valve both arranged coaxially with their axes alined with the longitudinal axis of said supporting handle, one of said valves extending

within said supporting handle and operable therefrom.

10. A drilling mechanism comprising a drilling motor and feeding means therefor, a supporting handle projecting from said mechanism, and means for controlling said motor and said feeding means including a rotatable valve and a reciprocable end seating valve contacting therewith and a pivoted valve actuating lever, both of said valves being arranged coaxially with their axes alined with the longitudinal axis of said supporting handle, and said lever being pivotally mounted at the outer end of said supporting handle.

11. A drilling mechanism comprising a drilling motor and a pressure fluid feeding means therefor, a supporting handle projecting from said mechanism, a throttle valve for controlling the fluid supply to said motor and to said feeding means, and a supplemental feed controlling valve arranged coaxially with said throttle valve, and means for operating said feed controlling valve carried by said supporting handle.

12. A drilling mechanism comprising a drilling motor and pressure fluid feeding means therein, a supporting handle projecting from said mechanism adapted to be grasped by the operator, a throttle valve for controlling the fluid supply to said motor, and means including a valve arranged coaxially with said throttle valve and associated with the supporting handle for enabling the operator to control said feeding means with but a single hand without removing said hand from said supporting handle.

13. A drilling mechanism comprising a drilling motor and pressure fluid feeding means therein, a supporting handle projecting from said mechanism adapted to be grasped by the operator, a throttle valve for controlling the fluid supply to said motor, and means including a valve arranged coaxially with said throttle valve and alined with the longitudinal axis of said handle and so arranged with respect to the latter as to enable the operator to control said feeding means with but a single hand without removing said hand from said supporting handle.

14. A drilling mechanism comprising a drilling motor and pressure fluid feeding means therein, a supporting handle project-

ing from said mechanism adapted to be grasped by the operator, a throttle valve for controlling the fluid supply to said motor, and means including a valve arranged coaxially with said throttle valve and a pivoted lever and associated with said handle for enabling the operator to control said feeding means with but a single hand without removing said hand from said supporting handle.

15. In a drilling mechanism comprising a drilling motor and pressure fluid feeding means therefor, coaxial controlling valves for said drilling motor and said feeding means, a supporting handle disposed coaxially with said valves and projecting from said mechanism, one of said valves extending within said supporting handle, a lubricant chamber disposed within said handle, and means for supplying lubricant from said chamber directly to said controlling valves.

16. In a drilling mechanism comprising a drilling motor and pressure fluid actuated feeding means therefor, a main controlling valve for said motor and feeding means, said valve having a hollow interior communicating with the source of fluid supply, a supporting handle disposed coaxially with said valve and projecting laterally from said mechanism, a feed control valve coaxial with said control valve and slidably longitudinally within said supporting handle, operating means for said feed control valve carried by said supporting handle, a lubricant chamber formed in said handle, and means for supplying lubricant from said handle directly to the hollow interior of said main controlling valve.

17. In a drilling mechanism, the combination of a drilling motor, a fluid actuated feeding element therefor, and a supporting handle extending laterally at one side of the drill and having a grasping portion at its outer extremity, of independently operable coaxially arranged valves, one of which controls fluid flow to both said feeding element and said motor and the other of which controls only the pressure in said feeding element, and controlling means for said latter valve carried by said supporting handle and including an operating portion disposed adjacent said grasping portion.

In testimony whereof I affix my signature.

ELMER G. GARTIN.

CERTIFICATE OF CORRECTION.

Patent No. 1,651,199.

Granted November 29, 1927, to

ELMER G. GARTIN.

It is hereby certified that error appears in the printed specification of the above numbered patent requiring correction as follows: Page 2, line 58, claim 3, after the word "thereto" strike out the comma, and insert the same after the word "therefrom" in line 59; same page, line 68, claim 4, after the word "thereto" strike out the comma; line 79, claim 5, after the word "therefor" strike out the comma and insert the same after the word "motor" line 78, same claim; line 119, claim 8, after the word "handle" insert a comma; page 3, line 9, claim 10, after the word "therewith" insert a comma, and line 13, same claim, after the word "handle" strike out the comma; and that the said Letters Patent should be read with these corrections therein that the same may conform to the record of the case in the Patent Office.

Signed and sealed this 10th day of January, A. D. 1928.

Seal.

M. J. Moore,
Acting Commissioner of Patents.
